UNITED STATES PATENT OFFICE.

EDWIN JOHN FLETCHER, OF NEW YORK, N. Y., ASSIGNOR TO THE WHITING MANUFACTURING COMPANY, OF SAME PLACE.

DESIGN FOR A CASE OR BOX.

SPECIFICATION forming part of Design No. 25,576, dated June 2, 1896.

Application filed April 8, 1896. Serial No. 586,756. Term of patent 7 years.

To all whom it may concern:

Be it known that I, EDWIN JOHN FLETCHER, a citizen of the United States, residing in the city of New York, in the county and State of New York, have invented a certain new and original Design for a Case or Box, of which the following is a specification, reference being had to the accompanying drawings, forming part thereof.

10 Figure 1 is a perspective view showing the case partly opened. Fig. 2 is a cross-sectional view showing the case in the fully-opened condition. Fig. 3 is a corresponding plan view.

15 The leading features of my design are the base, rectangular in outline with curved corners and rounded lower edges, the bed and its frame inclosed within the base and surrounded by an ornamental cord or rope like member, and the cover, matching the base in outline and having a top piece lying within the rounded upper edge of the cover, surrounded by a twisted ornament or cord corresponding to that in the base and lying within 25 the outer line of the cover.

The lower edge of the base is rounded off on all sides and smoothly joins the flat under surface. The upper edge is plane and extends inward to the bed-frame, which latter 30 is raised above such upper edge and is separated therefrom by an ornamental cord or

twisted member sunk in a groove surrounding the bed-frame on all sides.

The cover is of the same dimensions in plan as the base, and its lower plane edge matches closely to the upper edge of the latter when the case is closed. It is thicker than the base, and its upper outer edge is rounded, as shown. A top piece smaller than the cover has its corners curved to correspond thereto and its outer edge rounded down on all sides, meeting the rounded edge of the cover and producing a sharply-defined crease at the junction in which is laid a continuous cord or rope similar to the twisted ornamental member surrounding the bed-frame. The under face of the top piece is belled downward or slightly curved to produce a cushion-like effect and match to the swelled upper surface of the bed.

50 The whole presents a peculiarly tasty and attractive appearance.

I claim—

55 The design for a case or box, substantially as shown and described.

In testimony that I claim the invention above set forth I affix my signature in presence of two witnesses.

EDWIN JOHN FLETCHER.
